(57) **CLAIM**

The ornamental design for an adapter for affixing a magnetic sensor, as shown and described.

DESCRIPTION

FIG. 1 is a top perspective view of an adapter for affixing a magnetic sensor, showing our new design;

FIG. 2 is a bottom perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof;

FIG. 9 is a perspective view thereof with a lock opened;

FIG. 10 is a front elevational view thereof with the lock opened;

FIG. 11 is a left side elevational view thereof with the lock opened;

FIG. 12 is a top plan view thereof with the lock opened;

FIG. 13 is a cross-sectional view thereof, taken along the line 13-13 in FIG. 5;

FIG. 14 is a cross-sectional view thereof, taken along the line 14-14 in FIG. 3; and,

FIG. 15 is a cross-sectional view thereof, taken along the line 15-15 in FIG. 3.

The broken lines showing in FIGS. 13, 14 and 15 of the thickness and interior surface of the adapter for affixing a magnetic sensor are for environmental purposes only and form no part of the claimed design.
